Primary Examiner — Abraham Bahta(74) *Attorney, Agent, or Firm* — Medley, Behrens & Lewis LLC; Lorri W. Cooper(57) **CLAIM**

The ornamental design for a bar code for a pouch, as shown and described.

DESCRIPTION

FIG. 1 is a perspective view of the bar code for a pouch showing my new design;

FIG. 2 is a front plan view thereof, the rear plan view being a mirror image thereof without the bar code;

FIG. 3 is a right-side view thereof, the left side view being a mirror image thereof;

FIG. 4 is a bottom plan view thereof; and,

FIG. 5 is a top plan view thereof.

The broken line showing of portions of the bar code for a pouch in FIGS. 1-5 is included for the purpose of illustrating environmental structure and forms no part of the claimed design.
